UNITED STATES PATENT OFFICE

EDWIN ARCHER TURNER, OF NEW YORK, N. Y., ASSIGNEE TO THE STANDARD STOKER COMPANY, INCORPORATED, A CORPORATION OF DELAWARE

LOCOMOTIVE AND TENDER

Application filed November 20, 1929. Serial No. 402,434.

My invention relates to railway rolling stock and especially to improvements in the construction of stoker fired locomotives and their tenders. 5 The general object of the invention is the provision of a novel and improved construction of a stoker fired locomotive and its tender wherein the design is materially simplified, the weight reduced, cost of construction and 10 maintenance lowered and resulting in a more durable structure.

More particularly it is an object of the invention to provide in a locomotive and tender a construction in which the tender portion of 15 a stoker feed conduit forms an integral part of the tender and wherein the delivery portion of the stoker conduit is an integral part of the locomotive. And more specifically in which such integral stoker conduit portions 20 are flexibly united by a separable intermediate conduit section extending between the locomotive and tender.

Another and one of the main objects of my invention is the provision of a locomotive 25 having the delivery conduit of a stoker formed therewith as an integral and unitary part; or more specifically, my invention contemplates forming such conduit section integrally with the boiler, or the firebox foundation or mud ring; or integrally with the locomotive frame or cradle.

A further object of the invention consists 30 in forming the mud ring and the stoker delivery conduit integrally, and in forming deck supports integral with the conduit.

A still further object of my invention is 35 the provision of an integrally formed locomotive structure and stoker delivery conduit wherein that portion of the conduit exposed to the heat of the fire is replaceable.

These and other objects and advantages of 40 the invention which consists in the combination and arrangement of the parts and in certain features of construction will be apparent 45 and fully described in the following description when read in connection with the accompanying drawings, in which

Fig. 1 is a detail central vertical longitudinal section through the rear portion of a locomotive and the forward portion of its tender

with the fuel feeding conduit system thereof, also shown in similar section;

Fig. 2 is a detail plan view of Fig. 1 with some portions broken away;

Fig. 3 is a section on the line 3—3 of Fig. 1; 55

Fig. 4 is an isometric view of a novel mud ring structure;

Fig. 5 is a central longitudinal vertical section through the rear portion only of a locomotive having formed therewith and shown in similar section a modified form of the novel mud ring and conduit structure;

Fig. 6 is a plan view of Fig. 5 with portions broken away;

Fig. 7 is a forward elevation of the firebox 65 backwall of Fig. 5 and looking at the backwall from a position within the firebox and with certain parts of the feed mechanism being removed to best illustrate the backhead construction; 70

Fig. 8 is a fragmentary view of the locomotive portion illustrated in Fig. 1 and which illustrates a modification of the invention wherein the mouth or delivery portion of the feed conduit is replaceable; 75

Fig. 9 is a plan section on line 9—9 of Fig. 8;

Fig. 10 is a forward elevation of the backhead structure of Fig. 8 taken from a position within the firebox and in which parts of the 80 feed system within the firebox are removed to best illustrate the form of the backhead;

Fig. 11 is a fragmentary view similar to Fig. 1 but illustrating a modified form of the invention; and

Fig. 12 is a vertical section on line 12—12 of Fig. 11.

Heretofore it has been the practice in the railroad industry to design the locomotive and its tender without much consideration 90 being given to the design or application of stoker mechanism, although the stoker has been and is now recognized as essential to the modern steam locomotive. The stoker of necessity has been constructed to be applied to existing locomotive and tenders or to established designs for new construction. 95

The installation requirements of the railroads differ widely and are conflicting. On some installations the stoker must be designed 100

not to obstruct space in the cab; in others the grate area must not be reduced by reason of stoker application; on others the mechanism must not interfere with other locomotive accessories, while on others the fuel or water compartment of the tender must not be materially reduced. And in most all instances the weight and space occupied by the stoker apparatus is an important problem arising in connection with every individual installation. Many other conflicting requirements could be mentioned. These requirements insisted upon by the railroads lead to the design of many different types of stokers and complications in their installation with a resulting complicity of locomotive and tender construction.

My present invention permits compliance with the conflicting requirements without the complications of past practice and the invention contemplates designing the locomotive and its tender to best suit a desired stoker mechanism and wherein the stoker conduit system is incorporated as an integral part 25 of a locomotive and tender structure.

Referring now to the drawings, Figures 1 to 4 illustrate a preferred form of construction selected for the purpose of best describing the invention, although, it will be 30 recognized by those familiar with locomotives that under certain conditions, or design requirements specified, any of the other forms shown may be preferred, or still others not shown may be employed and be within the 35 spirit of this invention.

On the drawings and referring now particularly to Figures 1 to 4, the locomotive is generally represented at A, the tender as a whole at B, and the articulated coupling gear 40 interposed between as at C. Fuel is carried from the tender and fed to the locomotive by suitable mechanism, hereinafter described, through a flexible conduit system indicated generally at D which comprises a rearward 45 trough section E formed integrally with the tender structure, a forward tubular or delivery section F formed integrally with the locomotive structure, and a telescoping conduit section G separable from the locomotive 50 and tender and which flexibly joins the rearward and forward conduit sections in communicating relationship in a manner to permit articulation between the locomotive and tender without breakage of the conduit sections or any of its associated parts. All of 55 these parts and the particular locomotive and tender construction are hereinafter more specifically described.

The locomotive A is of the usual construction except in that part to which this invention is directed. It includes a frame 10 and a boiler and firebox 11 having an 60 upstanding backhead 12 at the rear thereof. The firebox is provided with the customary grate as at 13. The locomotive cab is rep-

resented at 14 and its deck or floor indicated by the numeral 15. The tender B rearward of the locomotive is formed with an under frame 16 above which there is a body portion including a fuel bin 17 and a water compartment 18 separated from each other by the side slope sheets 19 and 20, the rear slope sheet 21, together with the trough E which is constructed to form with the slope sheets a closure between the fuel and water compartments as now explained.

As is well illustrated in Figure 3, the trough E is formed centrally and longitudinally of the main under frame 16 and comprises a substantially V-shaped cast portion 22 formed above the main under frame and connected therewith by the perforated support 23 and the solid support 24. The rearward end of the V-trough is closed by a vertical wall 25 forming one of the sidewalls of 25 a gear housing compartment 26 which is formed by the top wall 27, the rear vertical wall 28, and sidewalls 29 and 30.

The sidewall 30 extends to the forward end of the tender and forms with the support 24 and the frame 16 a longitudinally extending compartment 31 open at its forward end and at its rear end opening into the gear housing compartment 26. The compartment 31 enables inspection or maintenance of the 95 driving gears 32, 33 and the trough drive shaft 34 of the stoker mechanism. An additional inspection opening 35, see Figure 1, is provided in the under frame 16.

An upstanding wall 36 transversely of and 100 being cast with the under frame 16 is arranged to partially close the front end of the V-trough 22 and to serve as the forward wall for the water compartment beneath the tender deck 37. An opening 38 is provided in 105 this wall for the passage of fuel forwardly from the trough.

Horizontally and inwardly extending ledges 39, 40, are provided at the upper end 110 of the trough 22 to form a seat for slidable plates 41, which form a continuation of the tender deck. The sides of the trough 22 extend upwardly as at 42, 43, to receive the side slope sheets 19 and 20, which sheets are held thereto by welding or riveting in any suitable manner. Likewise the rear slope sheet 21 is attached to the top wall 27, of the gear housing compartment 26.

Thus it will be seen the rear and side slope sheets together with the trough formation of the under frame divide the fuel and water compartments in a manner to greatly simplify tender construction, reducing construction and maintenance cost, and providing more water space than in existing tenders.

The front end of the trough B is equipped with a projection 45 detachably secured to the front wall 36 in communication with the opening therein and formed with the projection 45 is a spherical flange 46 adapted to be 120 125 130

received in a spherical portion of the vertical-
ly split coupling member 47 carried by the
rear tubular section 48 of the conduit G. The
front section 49 of the conduit G telescopes
5 with the rear section and carries at its for-
ward end a spherical ball 50 cooperating with
a horizontally split spherical flange 51 on
the rear end of the rearwardly extending por-
tion 52 of the forward conduit section F, and
10 forms a flexible section between the forward
and intermediate conduit sections.

The forward conduit is formed integrally
with a new and novel mud ring 54. As best
shown in Figures 1 and 4, the conduit F ex-
15 tends through the plane of the backwall 12
and has a forward mouth portion 53 extending
into the firebox and opens upwardly
therein to deliver fuel at a height above the
normal level of the fire to a distributor 55
20 disposed in any suitable manner in the back
of the mouth portion substantially at the rear
of the fuel stream being delivered. This
mouth portion is protected from the heat of
the fire by an upstanding perforated protect-
25 ing wall 56 horizontally split and partially
surrounding the mouth portion. The protect-
ing wall is supported on the center grate
bar 57 of substantially wishbone shape of a
form well known in locomotive and stoker
30 construction.

The novel construction of the mud ring 54
together with its integral feed conduit sec-
tion F is clearly illustrated in Figure 4 read
in connection with Figures 1 and 2. The
35 mud ring may be of the usual construction
made in the form of a unitary casting bound-
ing the base of the firebox, or as conventionally
illustrated in Figure 4 it may be formed of
four straight sections welded or otherwise
40 attached at the corners and in which the
transverse rearward section 60 has formed
centrally therewith, the forward feed con-
duit section F. In this transverse section
there is an upwardly extended ring portion
45 61 of channel section having an archway or
opening therethrough at 62 which as will
be seen from Figure 1 forms the hand firing
opening of the backwall. Beneath this open-
ing and interposed between the upright sides
50 of the extended ring portion is disposed the
conduit section F in such manner as to form
with the mud ring proper a durable struc-
ture. A cross wall 63 extends laterally about
the tubular conduit portion 52, connecting
55 the upright sides of the ring portion to form
a closure beneath the opening 62. This wall
also serves to tie the conduit and mud ring
together. A horizontally disposed wall 64
extends rearwardly from the mouth portion
60 53 of the conduit to the upwardly extending
sides of the ring portion and merges there-
with to form a closure to prevent loss of fuel
and to prevent the flow of excess cold air into
the firebox at the base of the firing opening
65 or archway. This wall also ties the mouth

portion of the conduit with the ring like ex-
tension of the mud ring to form a solid struc-
ture. Any suitable number of strengthening
ribs as at 65, 66, may be provided to further
aid in the construction of a well built and
70 durable mud ring and stoker feed section.

Deck supports as at 67 and 67a are formed
integrally with the rearward section 52 of
the conduit F, extending upwardly therefrom
forming a solid support for the deck 15 as
75 best shown in Figure 1. This arrangement
supports the deck at a point where in past
practice it has been found difficult to firmly
brace the deck from the backhead.

In constructing the firebox and particu-
larly, the backhead, the inner and outer
sheets are apertured centrally and from their
lower marginal edges, this aperture is sub-
stantially an inverted U-shape in form and
in alignment with the inner margin of the
80 extended ring portion 61, of the mud ring.
The sheets can be secured to the mud ring and
its ring portion by riveting and welding or in
any customary manner. As shown in Figure
1 a firedoor ring 68 having an opening there-
85 in corresponding to the opening 62 of the
mud ring can be attached to the backhead in
alignment with the firing opening to pro-
vide a base for any conventional style of
90 firedoor, not shown.

This novel mud ring structure when in-
stalled with a boiler firebox insures a rigid
and firm backhead and in which any pre-
ferred form of stoker feed conduit can be
formed integrally therewith to deliver the
100 fuel to the firebox at any desired elevation,
and either within the firebox as shown in
Figure 1, or exteriorly thereof and dis-
charged through the opening 62 as shown in
the modification illustrated in Figures 5 to
105 7 as later explained.

Suitable mechanism is employed for crush-
ing and for conveying fuel through the con-
duit system D and distributing it over
the fire. For this purpose there is provided
110 a screw conveying means including a section
70 disposed within the trough E, and at its
rearward end operatively connected with the
gearing 32, 33 through a gear shaft 71; a
section 72 mounted within the conduit G and
115 universally connected as at 73 to the rear-
ward section; and a forward screw section 74
in the conduit F flexibly connected as at 75 to
the intermediate section and at its forward
end terminating short of the upturned por-
120 tion 53 of the forward conduit section. This
screw conveying means is driven from a
motor 76, see Figure 2, mounted on the loco-
motive and operatively connected with the
trough gearing through a flexible and ex-
125 tensible shaft 77 universally connected at its
one end at 78 to the motor and at its other
end at 79 to the trough drive shaft 34 mounted
in the bearings 80 of the trough structure. A
crusher member 81 is mounted above the

screw section 70 within the trough E in a position to act upon the fuel as it is being advanced forwardly.

In the operation of the stoker mechanism 5 fuel drops from the bin 17 through an opening created by the slideable plates 41 into the trough E and is conveyed forwardly through the conduit system by the screw sections 70, 72 and 74, driven at desired speeds from the 10 motor 76. The fuel rises from the forward end of the screw section 74 through the mouth or delivery conduit portion 53 into the path of a distributing steam blast adapted to issue from the distributor 55 and is spread in aerial 15 paths over the grate 13. Obviously, the arrangement of the stoker drive and the conduit system permits of movement between the locomotive A and the tender B.

It will be recognized from the foregoing 20 description of the preferred form of my invention that a very desirable construction of stoker fired locomotive and tender is provided wherein the stoker mechanism is of an extremely simplified form and in which the 25 fuel may be conveyed from the fuel bin of the tender and delivered to the firebox in a most direct path with a minimum of handling and consequently a minimum of grinding or pulverizing of the lump fuel.

30 A modified form of the invention is illustrated in Figures 5 to 7 inclusive, in which the tubular section 82 of the forward conduit F is entirely outside of the firebox 11 and through which the fuel is raised by any suitable means to a sufficient elevation for spreading it over the fire by means of a distributing blast issuing from a distributor head 83 across a delivery or floor portion 84 of the conduit F and the forward end of which extends somewhat into the firebox.

40 In this modification the novel mud ring 85 assumes a somewhat different shape than that heretofore described. It has formed therewith a ring member 86 substantially like that 45 of Figure 4 in which an archway 87 forming a firing opening through the backhead 12 is provided above the rearwardly extending conduit section 82 which is integrally formed with the mud ring. In this construction, as 50 shown in Figure 7, the inside sheet of the firebox backwall is of the same form as that used in present practice and having an aperture therein corresponding to the opening through the mud ring to provide for hand 55 firing, whereas, the outside plate will be the same as that used in the construction of the preferred form. The rear crosswall 88 of the mud ring extending between the upright sides of the ring member and constituting a 60 closure below the feed conduit extends horizontally at its upper end to form the bottom of the firing opening and it meets with the inner sheet to form a chamber 89 through which the boiler water may circulate entering 65 through the apertures 90 of the ring portion.

In this form of the invention the delivery or floor portion 84 is detachable from the conduit section 82 and is secured thereto in the seat 91 by suitable bolts as at 92. The distributor head 83 projects upwardly through the floor of the conduit section 82 rearward of the backhead 12 and at the rear of the delivery portion 84, there the fuel is swept forwardly into the firebox. Both the delivery member 84 and the distributor 83 cooperate in scattering the fuel uniformly over the fire.

70 This modification of the invention discloses in effect an outside feed conduit system, the forward section of which is formed with the mud ring and wherein the forward or delivery portion that extends into the firebox and subjected to the heat thereof is replaceable and can be detached from the mud ring structure. This form of the invention 75 also has cast therewith deck supports as at 80 93, 93a, extending laterally from the conduit F to rigidly support the deck 15.

85 Making the forward delivery or mouth portion of the stoker conduit replaceable is an important feature of my invention and in Figures 8 to 10 of the drawings, the form of feed system illustrated in the Figures 1 to 4 is shown, but wherein that portion of the forward conduit section that extends into the firebox is so constructed that it may be 90 removed, replaced or renewed.

95 Referring now to these figures the forward conduit F is formed of two sections, a rearward section 95 formed integrally with the mud ring and extending rearwardly therefrom; and a forward delivery or mouth section 96 in effect a continuation of the rearward conduit section, but which can be detached if found destroyed by the heat of the fire or if worn by the passage of the fuel 100 therethrough. The mouth portion has formed therewith a laterally extending flange 97 which when applied is received in the seat 98 formed by the U-shaped lug 99 disposed vertically on the wall portion 63 of the mud ring structure. As shown the forward section 100 terminates at or a little short of the detachable section of the conduit to permit this portion to be removed or replaced without the necessity of taking apart 105 or breaking down the stoker mechanism. If desired, the forward screw section can be extended into the mouth portion and the replaceable section can be renewed merely by disconnecting the locomotive and tender and separating them a sufficient distance to move the forward end of the screw rearward of the juncture of the two conduit sections 95 and 96 to permit the section 96 to be lifted 110 out of its position. Otherwise, the construction shown in these figures is identical with 115 that described in Figures 1 to 4.

120 Figures 11 and 12 on the drawings illustrate a somewhat different aspect of the invention wherein the forward conduit sec- 125 130

tion F is formed integrally with the framework of the locomotive.

In these figures the locomotive A is equipped with a conventional boiler firebox 101 having its component parts of conventional form. The frame structure includes a cradle casting 102 at the rear end portion of the locomotive. In the broader aspects of this invention it is immaterial whether the conduit F as shown in Figures 11 and 12 be formed integrally with the main frame, one of its members, or with the cradle casting as specifically disclosed in the drawings, but for the purpose of illustrating the various modifications of the invention the conduit is shown as being formed with the cradle casting. The conduit F in this modification of my invention comprises the integral section 103 and an upwardly extending replaceable delivery or mouth section 104. The replaceable section extends loosely into the firebox but is supported in the seat 105 in the forward curved portion of the integral section. The forward screw section 106 terminates at or adjacent this curving portion and forces the fuel upwardly through the replaceable section into the zone of action of the distributing blast issuing from the distributor head 107 acting to spread the fuel over the fire as is well known in practice. The replaceable conduit section is protected from the heat of the fire by a protecting grate wall 56 of identical form to that shown in Figure 1. Any suitable cast construction can be employed for forming the conduit section 103 of the forward conduit F with the frame or cradle casting 102, but for this purpose there is shown a rib structure generally indicated at 108.

It is believed apparent from the drawings and description that my invention provides a greatly improved stoker fired locomotive and tender construction of practical utility and one in which the construction is such as to be designed to incorporate the stoker feed conduit or its major sections as an integral and essential part of its structure with a consequent simplification in design, resulting in a reduction in weight, lowering of production and maintenance cost, and offering a more durable and rigid construction.

The specific illustrations shown in the drawings and corresponding specific description herein are used for the purpose of disclosure only, but it will be realized that the substance and spirit of the invention may be embodied in other forms as well as those shown.

I claim:

1. As a new article of manufacture, a locomotive mud ring having a stoker conduit section formed therewith.
2. As a new article of manufacture, a locomotive mud ring having the delivery section of a stoker formed therewith.
3. As a new article of manufacture, a locomotive mud ring having a stoker conduit section formed therewith, and means formed integrally with said conduit section for supporting a deck.

4. A locomotive mud ring having formed integrally on one of its sections an upwardly extended ring portion, said portion adjacent its base having a stoker conduit section formed therewith and at its upper portion formed with an opening above said conduit section adapted to bound the hand firing opening of a boiler backwall.

5. In a locomotive, a boiler and firebox with a backhead at the rear thereof, a mud ring for said firebox, and a fuel conveyor conduit cast integral with said mud ring.

6. In a locomotive, a boiler and a firebox with a backhead at the rear thereof, a mud ring for said firebox, and a fuel transferring conduit extending into said firebox, said conduit cast integral with said mud ring.

7. In a locomotive, a boiler and a firebox with a backhead at the rear thereof, a mud ring for said firebox, and a fuel transferring conduit extending into said firebox and opening upwardly therein, said conduit cast integral with said mud ring and extending through the vertical plane of said backhead.

8. In a locomotive, a boiler and a firebox with a backhead at the rear thereof, a cab and a deck therefor, a mud ring for said firebox, and a fuel transferring conduit section cast integral with said mud ring and means formed with said conduit section for supporting said deck.

9. In a locomotive having a boiler and a firebox with a backhead at the rear thereof and a tender with a fuel bin, a mud ring for said firebox, and a fuel feeding conduit system for transferring fuel from the fuel bin of said tender to said firebox including a conduit section cast integral with said mud ring and delivering fuel through the backhead of said firebox.

10. In a locomotive, a boiler and a firebox with a backhead at the rear thereof, a mud ring for said firebox, and a fuel transferring conduit including a forward section cast integral with said mud ring and communicating with said firebox, and a telescoping section flexibly connected with the rearward end of said forward section.

11. In a locomotive, a boiler having a firebox with a backhead at the rear thereof, a mud ring for said firebox including a rearward transverse section forming the base of said backhead, a stoker feed conduit formed integrally with the transverse section of said mud ring and extending rearwardly from said backhead, and a detachable mouth portion communicating with the forward end of said conduit section and extending within said firebox.

12. In a locomotive, a boiler firebox having a backhead and a mud ring with a stoker

feed conduit formed therewith and extending rearwardly from and outside of said backhead, and a stoker feed member in said firebox forming a continuation of said feed conduit and being detachable from said mud ring.

13. In a locomotive, a mud ring having a stoker conduit section formed therewith and a replaceable mouth portion communicating with the forward end of said conduit section.

14. In combination with a locomotive including a firebox and mud ring and a tender having a fuel bin, a stoker having a fuel transferring conduit system including a trough adapted to receive fuel from the fuel bin of said tender, said trough being integrally formed with said tender, an intermediate telescoping section, and a forward section on the locomotive formed integrally with said mud ring.

15. A locomotive mud ring having formed integrally with one of its sections a stoker conduit and an upstanding wall surrounding said conduit and extending thereabove, that portion of said wall above said conduit being apertured to provide a firing opening.

16. A locomotive mud ring having formed integrally with one of its sections a stoker conduit and a horizontally disposed wall tying said conduit to said section.

17. A locomotive mud ring having formed integrally with one of its sections a stoker conduit and horizontally and vertically disposed walls tying said conduit to said section.

In testimony whereof I affix my signature.
EDWIN ARCHER TURNER.
